(57) **CLAIM**

The ornamental design for intercommunication apparatus, as shown and described.

DESCRIPTION

FIG. 1 is a top perspective view of the intercommunication apparatus showing our new design;

FIG. 2 is a perspective view from below thereof;

FIG. 3 is a front view thereof;

FIG. 4 is a right side view thereof;

FIG. 5 is a left side view thereof;

FIG. 6 is a plan view from above thereof; and,

FIG. 7 is a plan view from below thereof.
